SPIRAL TOOL DRIVER

Roy Corella, Garvey, Calif.

Application October 22, 1951, Serial No. 252,529

2 Claims. (Cl. 145—53)

1

The present invention relates to new and useful improvements in speed tools of a type employing the use of a spirally grooved shaft with a handle movable longitudinally of the shaft and carrying a part engaged in the groove to translate the reciprocating motion from the handle to a rotary motion of the shaft, and the primary object of the invention is to provide an improved means for quickly releasing the driving engagement between the handle and shaft to permit movement of the handle without turning the shaft.

Another object of the invention is to provide a mechanism of this character of a more simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is an enlarged vertical sectional view of the device, on line 2—2 of Fig. 3, a fragment of the spirally grooved shaft being shown in elevation; and

Figure 3 is a transverse sectional view taken on a line 3—3 of Figure 2.

Referring now to the drawing in detail, wherein for the purpose of illustration I have disclosed a preferred embodiment of the invention, the numeral 5 designates a shaft having a spiral groove 6 therein and provided at one end with a socket 7 for attaching a ratchet type wrench or other suitable tool (not shown) thereto while the other end of the shaft 8 is constructed for interchangeably attaching wrench sockets 9 of different sizes thereto.

A sleeve 10 is positioned on the shaft for sliding forwardly and backwardly thereon, the sleeve being welded or otherwise suitably fixed to a handle 11. The end of the handle adjacent the sleeve is formed with a longitudinal bore 12 in which a driving pin 13 is slidable through an opening 14 in the sleeve to enter the groove 6 of the shaft. The pin 13 is normally held in a retracted position by a coil spring 15 positioned in the bore 12 and bearing against the flange 16 on the pin.

The rear end of pin 13 is engaged by a trigger 17 which is pivoted adjacent one end on a pin 18 positioned transversely in a notch 19 formed in one edge of the handle 11.

In the operation of the tool the driving pin 13 is normally held in its retracted position by the

2

coil spring 15, which also holds the trigger 17 projecting outwardly at one side of the handle, as shown in Figure 2 of the drawing. Sleeve 10 and handle 11 are then free to slide longitudinally on shaft 5 to position the handle at either end of the shaft.

Inward pressure on trigger 17 will project pin 13 through opening 14 of sleeve 10 to enter the groove 6 of shaft 5 whereby the longitudinal movement of the handle along the shaft will cause the shaft to rotate and thus drive a tool connected to one end of the shaft.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A tool comprising a spirally grooved shaft, a sleeve slidable on the shaft, a handle fixed to the sleeve, there being a bore through the side of said sleeve and extending into said handle, a driving pin slidably carried in said bore for movement into and out of engagement in the groove of the shaft to rotate the shaft upon a sliding movement of the handle, spring means retracting the pin from said groove, and means pivoted to the handle for projecting the pin into said groove.

2. A tool comprising a spirally grooved shaft, a sleeve slidable on the shaft, an elongated handle one end of which is fixed to the sleeve, there being a bore through the side of said sleeve and leading into said handle, a driving pin in said bore slidably carried by the handle for movement into and out of engagement in the groove of the shaft to rotate the shaft upon a sliding movement of the handle, spring means retracting the pin, and a trigger pivoted at one side of the handle and engaging the pin to project the latter into said groove.

ROY CORELLA.
